[57] CLAIM

The ornamental design for a bicycle speedometer, as shown.

DESCRIPTION

FIG. 1 is a front elevational view of a bicycle speedometer showing my new design;

FIG. 2 is a rear elevational view;

FIG. 3 is a left side elevational view;

FIG. 4 is a right side elevational view;

FIG. 5 is a top plan view;

FIG. 6 is a bottom plan view; and,

FIG. 7 is a top, front and left side perspective view thereof, the broken line showing of a partial bicycle handle bar is environmental and form no part of the claimed design.

FIG. 5

FIG. 3

FIG. 1

FIG. 4

FIG. 6

FIG. 2

FIG. 7
